CLAIM

The ornamental design for a stand with cameras, as shown and described.

DESCRIPTION

FIG. 1 is a top perspective view of a first embodiment of a stand with cameras showing our new design in a used condition.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a top perspective view of a second embodiment of a stand with cameras showing our new design in a used condition.

FIG. 9 is a front view thereof.

FIG. 10 is a back view thereof.

FIG. 11 is a left side view thereof.

FIG. 12 is a right side view thereof.

FIG. 13 is a top view thereof; and,

FIG. 14 is a bottom view thereof.

The broken lines illustrate environmental features that form no part of the claimed design.

1 Claim, 8 Drawing Sheets
